UNITED STATES PATENT OFFICE.

OTTO W. MIELENZ, OF PHILADELPHIA, PENNSYLVANIA.

CELLAR DOOR.

Application filed October 8, 1923. Serial No. 667,338.

To all whom it may concern:

Be it known that I, OTTO W. MIELENZ, a citizen of the United States, residing at Philadelphia, in the county of Philadelphia and State of Pennsylvania, have invented 5 certain new and useful Improvements in Cellar Doors, of which the following is a specification.

This invention relates to improvements in 10 cellar doors and particularly that type of door which is positioned in a sidewalk or the like.

An important object of the invention is to 15 provide a door which is compact and durable of construction and rests flush with the sidewalk when closed.

Another object of the invention is the provision of a door which will efficiently drain 20 rain water or the like therefrom.

Other objects and advantages of this invention will be apparent during the course 25 of the following description.

In the accompanying drawings forming a part of this specification and in which like 30 numerals are employed to designate like parts throughout the same:

Figure 1 is a plan view of the device in 35 position,

Figure 2 is an enlarged view of one of the 40 details,

Figure 3 is a vertical sectional view taken on the line 3—3 of Figure 1,

Figure 4 is an enlarged sectional view of 45 the door hinges in closed position, and

Figure 5 is a similar view showing the 50 door hinge in an open position.

In the drawings, wherein for the purpose of illustration is shown the preferred embodiment of my invention, the numeral 10 55 designates the door frame as a whole, said frame consisting of four channel members 11 which constitute the longitudinal and transverse bracing members. The ends of the channel members 11 are united at the 40 corners of the frame by the channel braces 12 which are of special form and adapted to receive the channels therein and may be bolted or riveted as desired. In order to prevent movement of the special channel 45 braces 12 they are provided with anchor straps 13, said anchor straps extending beyond the braces and being embedded in the concrete or the like.

Door hinges denoted as a whole by the 55 numeral 14 are fastened to the inner corners of the channel braces 12. The construc-

tion of the hinges 14 comprises a bracket 15 which is provided with openings for the reception of screws 16 or the like, and a transverse plate 17 which is secured to the bracket by means of rivets 18 or the like. A like plate 19 is secured to a door and adapted to rest upon the first mentioned plate 17 in the closed position of the hinge. A lever 20 which is bent at the desired angle is pivoted to the plate 19 as at 21, the pivot 21 being stationary in the plate and permitting the lever 20 to swing thereon. The opposite end of the lever 20 carries a pin 22 which is slidably mounted in an elongated slot 23 in the plate 17, thereby permitting transverse movement of the pin along said plate. A similar lever 24 is likewise secured to the plates 17 and 19 but in inverted relation, this arrangement of levers permitting 60 swinging movement being imparted to the plates 19 carrying a pair of doors 25 and 26. The swinging door 25 carries the transverse channel 27 secured to the outer edge thereof, said channel being strengthened by an angle iron 28 fastened beneath same and extending along its outer edge. A sliding bolt 29 is positioned at one end of the door and secured thereto by the strap 30 which controls the movement of said bolt. A commonly used type of sliding catch lock 31 is 65 fastened to the door 26 and so positioned as to allow the latch to slide under the channel 27 and preventing upward movement of the doors. In some instances it may be advisable to provide a weather strip 32 to prevent accumulation of rain water or the like over 70 the doors.

It is obvious from the preceding description that a compact and durable door for 75 cellars and the like is provided, and advantages over like devices now in use are apparent. In closed position the transverse center channel 27 and its reinforcing angle iron 28 are fitted into special openings in 80 the cross channels 11 and rest thereon, thereby supporting one of the doors. The other door rests upon one edge of the channel and is locked beneath same by the sliding catch lock 31. In an open position a guard rail 85 may be inserted by providing suitable apertures in the angle iron 28 and securing a clip or the like to the opposite door, the rail being inserted and thereby held in position.

It is to be understood that the form of 90 my invention herewith shown and described

is to be taken as the preferred example of the same, and that various changes in the shape, size, and arrangement of parts may be resorted to without departing from the 5 spirit of my invention or the scope of the subjoined claims.

Having thus described my invention, I claim:

1. A device of the character described, 10 comprising a frame, a pair of doors arranged upon said frame, a series of plates carried by said frame adjacent the corners thereof, plates carried by said doors and arranged adjacent said first mentioned 15 plates so as to provide a plate carried by said door and a plate carried by said frame adjacent each corner of said frame, a pair of levers at each corner of said frame, said levers being pivotally connected together 20 and each having one end pivotally connected to one of said plates, and means for connecting the opposite ends of said levers to said plates to permit a limited sliding movement of one end of said levers with relation 25 to said plates.
2. A device of the character described, comprising a frame, a pair of doors arranged upon said frame, a series of plates carried by said frame adjacent the corners 30 thereof, plates carried by said doors one arranged adjacent each of said first mentioned plates, each of said plates having a longitudinal slot therein, a pair of levers at each corner of said frame, said levers 35 being pivotally connected together and each having one end pivotally connected to one of said plates, and pins carried by the opposite ends of said levers and slidably received in said slots when said doors are opened and closed.

3. A device of the character described, 40 comprising a frame, a pair of doors arranged upon said frame, a series of plates carried by said frame adjacent the corners thereof, plates carried by said doors one arranged adjacent each of said first mentioned 45 plates, each of said plates having a longitudinal slot therein, a pair of levers at each corner of said frame, said levers being pivotally connected together and each having one end pivotally connected to one of said 50 plates, and pins carried by the opposite ends of said levers and slidably received in said slots, said slots being of a length sufficient to permit said doors to be swung past a dead center to hold the same in an open or 55 raised position.

4. A device of the character described, comprising a frame, a pair of doors arranged upon said frame, a series of plates carried by said frame adjacent the corners thereof, plates carried by said doors and arranged to lie above said first mentioned plates when said doors are in a closed position 60 so as to provide a pair of parallel plates at each corner of said frame, each of said plates having a longitudinal slot therein, a pair of levers at each corner of said frame, said levers being arranged upon the opposite sides of said plates and being pivotally connected together and each having 65 one end pivotally connected to one of said plates, and pins carried by the opposite ends of said levers and arranged to slide in said slots when said doors are opened and closed. 70

In testimony whereof, I have affixed my 75 signature.

OTTO W. MIELENZ.
